A. E. CHAMBERLAIN AND JOHN B. CROWLEY, OF CINCINNATI, OHIO,
ASSIGNORS TO CHAMBERLAIN & CO., OF THE SAME PLACE.

Design No. 2,662, dated June 4, 1867.

DESIGN FOR A COOK'S STOVE.

The Schedule referred to in these Letters Patent and making part of the same.

TO WHOM IT MAY CONCERN:

Be it known that we, A. E. CHAMBERLAIN and JOHN B. CROWLEY, both of Cincinnati, Hamilton county, Ohio, have invented a new Design for a Cooking-Stove, which design is represented in the accompanying drawing which forms a part of this specification.

We claim as our invention, and desire to secure by Letters Patent—

The design for a cooking-stove, substantially as represented in the accompanying drawing.
In testimony of which invention we hereunto set our hand.

A. E. CHAMBERLAIN,
JOHN B. CROWLEY.
